UNITED STATES PATENT OFFICE.

HENRY KREISHELD, OF MANSFIELD, OHIO, ASSIGNOR TO WESTINGHOUSE ELECTRIC PRODUCTS COMPANY, A CORPORATION OF MICHIGAN.

CONTACT TERMINAL.

Application filed November 20, 1919. Serial No. 339,264.

To all whom it may concern:

Be it known that I, HENRY KREISHELD, a citizen of the United States, and a resident of Mansfield, in the county of Richland and State of Ohio, have invented a new and useful Improvement in Contact Terminals, of which the following is a specification.

My invention relates to electrical contact devices and particularly to such contact devices of the plug-and-socket type as are used on electrically heated apparatus.

The object of my invention is to provide a contact device of the above type that shall be relatively inexpensive to manufacture and that shall have greater contact surface and greater contact pressure between the co-operating parts than have pertained to devices of this character which have heretofore been employed.

Heretofore, the socket members of such devices have consisted of a number of parts suitably secured together to engage and grip the plug member and, very frequently, the contact area of the two parts in actual engagement has been insufficient to prevent overheating of the contact device.

In practicing my invention, I provide a single-piece socket made from thin sheet metal, so cut and bent as to form a body portion and two longitudinally-extending end or contact portions, each contact portion having an arcuate contact surface. The end portions are so formed that one part thereof is resiliently supported by the body portion and, in turn resiliently supports the other part.

Referring to the single sheet of drawings, Figure 1 is a top plan view of a sheet-metal stamping from which the finished contact socket embodying my invention is made; Fig. 2 is a top plan view of a finished socket and a co-operating contact plug, and Fig. 3 is a view, partly in section, of an insulating casing having two contact sockets mounted therein; Fig. 4 is a top plan view of a sheet metal stamping, from which a modification of my device may be made, and Fig. 5 is a top plan view of a finished socket, made from the stamping shown in Fig. 4, and a co-operating contact plug.

Referring to Fig. 1, a contact-socket blank comprises a body portion 1, two side extensions 2, an end extension 3 and two end portions 4 and 5 that project from the body portion 1 oppositely to the portion 3 to form

a relatively narrow slot 6 which extends from their outer ends to within a short distance of the body portion. The respective end portions 4 and 5 are divided into two parallel parts 4^a and 4^b and 5^a and 5^b by means of slots 7, parallel to the slot 6 and extending from near the outer ends of the portions 4 and 5 to the body portion 1. The parts 4^b and 5^b project longitudinally from the body portion and the parts 4^a and 5^a are connected to the outer ends of the parts 4^b and 5^b.

Fig. 2 shows the finished contact socket, in which the longitudinal extension 3 is disposed parallel to, and against, the body portion, it having been return-bent to this position, a circular opening 8 having been drilled through it and the body portion and tapped to receive a binding screw 9 (Fig. 3). The lateral extensions 2 have been bent to positions at right angles to the body portion, on the same side thereof and parallel to each other, and their outer edges have been bent laterally, as indicated at 3^a, for a purpose to be hereinafter set forth. The end portions 4 and 5 have been transversely bent into arcuate form, each of the parts 4^a and 4^b—5^a and 5^b covering approximately one-fourth of the periphery of the co-operating contact plug 10. In forming the contact socket, the outer ends of the portions 4 and 5 may be so pressed toward each other that the adjacent edges of the parts 4^b and 5^b nearly or quite touch each other, whereby the diametral distance between the parts 4^a and 5^a and 4^b and 5^b will be less than the diameter of the plug 10. If the outer end of the contact socket be forced over the end of the plug 10, the outer ends of the portions 4^a, 4^b and 5^a, 5^b will be separated thereby. As the socket is pushed farther upon the plug 10, the distance between the adjacent sides of the inner ends of the parts 4^a and 5^a will be increased, as may be required by the diameter of the plug 10, until, when the two parts of the contact device are in normal co-operative relation, the four parts of the socket are pressed tightly against the plug 10, thus providing a relatively large contact area for the passage of the current between the socket and the plug.

Fig. 3 shows the lower half of an insulating casing 11 having two contact sockets mounted therein and two conductors 12 and 13 of a twin conductor cable 14 con-

2
nected to them by means of screws 9. The laterally bent edges 3^a fit loosely into grooves 15 and serve to hold the contact sockets in position in the casing 11. A cylindrical opening 16 is provided in the casing 11 to receive a bolt (not shown) for clamping together two similar casing halves to form a complete casing.

Figs. 4 and 5 show a slightly modified form 10 of contact socket. A sheet metal blank 17 comprises a body portion 18, a short projection 19 and two relatively long projecting portions 20 and 21. The outer half of each 15 of the portions 20 and 21 is transversely bent into trough shape, each portion covering approximately 180° of arc. The outer part of each of the end portions 20 and 21 is then return-bent upon the inner part, at the lines 22, substantially to positions shown in Fig. 20 5. The end portions are then bent toward each other along the broken lines 23 until their outer surfaces are substantially parallel and at angles of 90° with the surface of the body portion 18.

25 Fig. 5 shows the contact socket completely formed, the extension 19 having been return-bent into engagement with the body portion 18 and a circular opening 8 having been drilled through both portions and 30 tapped to receive a binding screw 9. The outer ends of the parts 20 and 21 are bent outwardly, as indicated at 20^a and 21^a, to co-operate with grooves 15 in a casing 11 to hold the contact sockets therein, as indicated in Fig. 3. If the outer end of the contact socket 17 is pushed over the rounded end of the contact plug 10, the distance between the outer ends of the portions 20 and 21 will be increased, while the distance between the inner ends will be slightly decreased. As the socket member 17 is pushed farther upon the contact plug 10, the distance between the inner ends of the trough shaped parts will be increased to conform 45 to the diameter of the plug 10.

It may be noted that in the device shown in Fig. 2, the contact portions 4^b and 5^b are inherently resilient only, while the contact portions 4^a and 5^a are both inherently resilient and dependently resilient. In the device shown in Figs. 4 and 5, the contact por-

tions are both inherently and dependently resilient, while the outer portions are inherently resilient only. Substantially all of the co-operating surface of the plug and 55 sockets are in engagement and the relatively high pressure between the co-operating members insures a low operating temperature of the contact device. The unitary structure of the device permits of its being 60 manufactured quickly and by simple methods and insures the permanency of the relative positions of the various parts of the device.

While I have shown a specific structure 65 of the device embodying my invention, various changes may be made therein without departing from the spirit and scope of my invention, and I desire that only such limitations shall be placed thereon as are imposed by the prior art or are specifically set forth in the appended claims.

I claim as my invention:

1. A unitary terminal device for electrical conductors comprising a body portion having 75 three extensions, one of said extensions being return-bent against said body portion and two of said extensions being bent at right angles to said body portion on the same side thereof and parallel to each other, and a plurality of longitudinally slotted end portions, transversely bent to arcuate shape to form a tubular socket of circular cross section.

2. A unitary terminal socket comprising a 85 body portion and a plurality of extensions, one of said extensions being return bent against said body portion, two of said extensions being bent at right angles to said body portion on the same side thereof and 90 parallel to each other and another extension having a central slot extending longitudinally from its outer edge, and two laterally spaced parallel slots extending longitudinally from its inner edge, said extension being so bent transversely as to form a slotted tube of circular cross section.

In testimony whereof, I have hereunto subscribed my name this 6th day of November, 1919.

HENRY KREISHELD.
